DOOR HINGE

Richard F. Marquis, Bellefontaine, Ohio

Application March 21, 1958, Serial No. 722,964

11 Claims. (Cl. 16—164)

2

The door 12 has a hinge end 14 to which a butt plate 15 is suitably attached, for example, by welds or screws. The plate 15 has two bearing sleeves 16 and 17 (see Fig. 3) through which door pins 18 and 19 respectively extend in spaced relation transversely of the door. In the door jamb 13, there are two vertically spaced horizontal bearing plates 20 and 21 (see Fig. 4) which form a hinge receiving space that outwardly opens through the jamb face and holds two vertical, parallel jamb pins 22 and 23. These pins are spaced inwardly one from the other transversely of the jamb adjacent to its outer side.

A hinge leaf 24 is mounted on the pin 22 and has a jamb leg or straight portion 25, the length of which is slightly greater than the distance from the pin 22 to the edge of the jamb 13. It also has a door leg or generally arcuate portion 26 which is spaced laterally from the pin 22 a distance at least as great as the distance from the pin 22 to the edge of the jamb 13. The straight portion 25 has at its free end a bearing sleeve 27 through which the pin 22 extends, and the arcuate portion 26 has at its free end a bearing sleeve 28 through which the pin 18 extends. A guide link 29 is disposed lengthwise around the hinge leaf 24 and has a jamb leg or straight portion 30, the length of which is at least as great as the distance from the pin 23 to the door jamb 13 plus the thickness of the leaf 24. The straight portion 30 of the link 29 has an integrally connected door leg or generally arcuate portion 31 which is spaced laterally from the pin 23 a distance at least as great as the length of the straight portion 30. The straight portion 30 and the arcuate portion 31 have respective bearing sleeves 32 and 33 at their outer ends through which the pins 23 and 19 respectively extend.

The jamb pins 22 and 23 should be located in a plane roughly perpendicular to a plane extending through the door pins 18 and 19. If the pin 23 is too far to the rear, away from the exterior of the vehicle, the door will not swing outwardly to a sufficient extent because the arcuate paths of the pins 18 and 19 around the pins 22 and 23 will intersect and cause the door to jam. On the other hand, if the pin 23 is too far forward, toward the exterior of the vehicle, the arcuate paths of the pins 18 and 19 will tend to diverge too rapidly and the door 12 cannot be further opened when the minimum distance between the arcuate paths of the pins 18 and 19 is greater than the distance between the pins 18 and 19. The relationships of the pins is preferably such that the distance between the two arcs is less than the distance between the pins 18 and 19 when the hinge leaf 24 and the guide link 29 are both against the door jamb, as shown in Fig. 2. Fig. 2 also shows an ellipsoidal arc through which the hinge end 14 of the door travels. The latch side of the door, of course, follows a similar arc.

The shapes of the hinge leaf 24 and the guide link 29 enable the entire hinge to be concealed within the jamb port when the door 12 is closed. Although the leaf and link are shown with the latter disposed around the former, the hinge assembly will work equally effectively if the hinge leaf and guide link are spaced apart along the hinge end 14 of the door 12. In either case, a hinge according to the invention comprises a hinge leaf having a jamb leg pivotally attached to the jamb and a door leg pivotally attached to the door, and a guide link

This invention relates to a door hinge and more particularly to an improved, articulated door hinge of the concealed type that enables a door associated therewith to be opened in a more effective manner.

A concealed hinge according to the invention enables a door to be opened fully so that all portions thereof are beyond the limits of the door opening. An opening of maximum area is thereby provided and a greater access area is available than is possible with conventional hinges. A hinge according to the invention is, therefore, particularly advantageous for door openings through which large objects are transported and also where fully unobstructed openings are desirable as in busses, streetcars and the like. The new hinge also enables a door to travel in a path having a shape of an ellipsoid segment, with the door traveling in a relatively flat arc when first opened and in a more acute arc when further opened. The door thus does not interfere with another door or door jamb.

It is, therefore, a principal object of the invention to provide an improved, concealed door hinge which enables a door to be opened clear of the door opening.

Other objects of the invention will be suggested from the following detailed description of a preferred embodiment thereof, reference being made to the accompanying drawing, in which:

Fig. 1 is a view in cross section of a portion of a door and a portion of a vehicle body, showing a hinge according to the invention, with the door in closed position;

Fig. 2 is a view similar to Fig. 1 with the door in an open position;

Fig. 3 is an enlarged view in perspective of a portion of the hinge; and

Fig. 4 is a view in perspective of portions of the hinge and its mounting.

A hinge according to the invention is particularly intended for use in connection with ambulance or funeral coaches where a maximum door opening is desired to establish a better access for the insertion and removal of stretchers, caskets, and the like. The invention is not to be limited in any manner to vehicles however, because it can be equally well used in conjunction with doors for buildings, ships, houses, refrigerators, safes, and other almost unlimited applications.

Referring to the drawings, and more particularly to Fig. 1, a hinge 11 embodying the invention is shown in connection with a portion of a door 12 and a door hinge post or door jamb 13, which is part of a vehicle body.

having a jamb leg pivotally attached to the jamb and a door leg pivotally attached to the door.

I wish it understood that my invention is capable of various modifications which can be made without departing from the scope of the invention as defined in the appended claims.

What I claim is:

1. A door hinge comprising a hinge leaf and a guide link, said hinge leaf having a straight portion for pivotally attaching to a door jamb and an arcuate portion for pivotally attaching to the hinge edge of a door, said guide link having a straight portion and an arcuate portion, with the straight portion of the guide link longer than the straight portion of the hinge leaf and for pivotally attaching to the jamb, said link arcuate portion being spaced from the link jamb pivot a greater distance than said leaf arcuate portion is spaced from the leaf jamb pivot, and said arcuate link portion adapted to be pivotally attached to the hinge edge of the door.

2. A door hinge comprising a hinge leaf and a guide link, said hinge leaf having a straight portion and an arcuate portion, said straight portion adapted for pivotally attaching to a door jamb and said arcuate portion adapted for pivotally attaching to the hinge edge of an associated door adjacent to its outer side, said guide link having a straight portion and an arcuate portion with the straight portion adapted for pivotally attaching to the door jamb at a distance from the edge of said jamb greater than the distance between said leaf jamb pivot and the edge of said jamb, and said link arcuate portion adapted for pivotally attaching to the hinge edge of the door farther from the outer side thereof than is the leaf door pivot.

3. A door hinge comprising a hinge leaf and a guide link, said leaf having a straight portion and an arcuate portion with the straight portion adapted for pivotally attaching to a door jamb and the arcuate portion adapted for pivotally attaching to the hinge edge of an associated door adjacent to its outer side, said guide link having a straight portion and an arcuate portion with the straight portion longer than the leaf straight portion and adapted for pivotally attaching to the jamb at a distance from the edge of the jamb greater than the distance from the edge of the jamb to said leaf jamb pivot, the arcuate portion of the link being spaced from the link jamb pivot a distance greater than the distance said leaf arcuate portion is from the leaf jamb pivot, and said link arcuate portion being adapted for pivotally attaching to the hinge edge of the door at a distance from the outer side of the door greater than the distance the leaf door pivot is from the exterior surface of the door.

4. A door hinge comprising a hinge leaf and a guide link, said leaf having a straight portion and an arcuate portion with said straight portion adapted for pivotally attaching to a door jamb and said arcuate portion adapted for pivotally attaching to the hinge edge of an associated door, said guide link having a straight portion and an arcuate portion, with the straight portion adapted to be pivotally attached to the door jamb in spaced relation to and at the side of the leaf jamb pivot opposite the door, and said leaf arcuate portion adapted to be pivotally attached to the hinge edge of a door in a direction from said leaf door pivot opposite to the direction in which the door opens.

5. A combination as called for in claim 4 in which the length of said leaf straight portion exceeds the distance from the leaf jamb pivot to the edge of the door jamb, and said leaf arcuate portion is, at all portions thereof, at a distance from the leaf jamb pivot at least as great as the length of said leaf straight portion, and the length of said link straight portion is at least as great as the distance from said leaf jamb pivot to the edge of the door jamb plus the thickness of the hinge leaf, and said link arcuate portion is, at all points, a

distance from the link jamb pivot at least as great as the length of said link straight portion.

6. A hinge for a door to pivotally connect the same to a door jamb, said hinge comprising a hinge leaf, a guide link, said leaf having a jamb leg and a door leg, said legs being integrally connected at an angle, said jamb leg being adapted for pivotally attaching to the door jamb and said door leg being adapted for pivotally attaching to the hinge edge of the door, said guide link having a jamb leg and a door leg, also integrally connected at an angle with the jamb leg adapted for pivotally attaching to the jamb on the side of said leaf jamb pivot opposite the door, and said link door leg adapted for pivotally attaching to the hinge edge of the door in a direction from the leaf door pivot opposite to the direction in which the door opens.

7. An apparatus as called for in claim 6 in which the length of said leaf jamb leg exceeds the distance from its pivot to the edge of the door jamb, said leaf door leg being, at all portions thereof, at a distance from the leaf jamb pivot at least as great as the length of said leaf jamb leg, the length of said link jamb leg being at least as great as the distance from the leaf jamb pivot to the edge of the door jamb plus the thickness of said hinge leaf, and said link door leg being, at all portions thereof, a distance from the link jamb pivot at least as great as the length of said link jamb leg.

8. A hinge for a door to pivotally connect the same to a door jamb, said hinge comprising a hinge leaf and a guide link, said leaf having a jamb leg and a door leg with a jamb leg pivotally attached to the door jamb and with the door leg pivotally attached to the hinge edge of the door, the length of said jamb leg being greater than the distance from the leaf jamb pivot to the edge of the jamb, and said door leg being, at all portions thereof, a distance from the leaf jamb pivot greater than the length of said jamb leg, said guide link having a jamb leg and a door leg with the link jamb leg longer than the leaf jamb leg and pivotally attached to the jamb at a distance from the edge of the jamb greater than the distance from the edge of the jamb to the leaf jamb leg pivot, said link door leg being spaced from the link jamb pivot a distance greater than the distance said leaf door leg is from the leaf jamb pivot, and said link door leg being pivotally attached to the hinge edge of the door at a distance from the exterior surface of the door greater than the distance the leaf door pivot is from the exterior surface of the door.

9. A hinge assembly for a door to pivotally connect the same to a door jamb, said hinge assembly comprising a pair of spaced plates supported by the door jamb laterally to the longitudinal extent of the jamb and forming a recess between the plates, a hinge leaf having a jamb leg and a door leg integrally connected at an angle, said jamb leg being pivoted to said plates and said door leg being pivoted to the hinge edge of the door, a guide link having a jamb leg and a door leg also integrally connected at an angle, each leg of said guide link being longer than the corresponding leg of said hinge leaf, the link jamb leg being pivoted to said plates with a line through the link and leaf plate pivots extending laterally to the edge of the jamb, and said link door leg being pivoted to the hinge edge of the door with a line through the link and leaf door pivots extending laterally to the exterior surface of the door.

10. A hinge assembly for a door to pivotally connect the same to a door jamb, said hinge assembly comprising a pair of spaced plates supported by the door jamb and disposed laterally to the longitudinal extent of the jamb, a hinge leaf having a jamb leg and a door leg integrally connected at an angle, said jamb leg being pivoted to said plates and said door leg being pivoted to the hinge edge of the door, a guide link having a jamb leg and a door leg also integrally connected at an angle, each leg of said link being longer than the corresponding leg

of the hinge leaf with the link jamb leg pivoted to said plates on the side of said leaf plate pivot opposite the door, and said link door leg being pivoted to the hinge edge of the door in a direction from the leaf door pivot opposite the direction in which the door opens.

11. A hinge assembly for a door to pivotally connect the same to a door jamb, said hinge assembly comprising a pair of spaced plates disposed laterally to the longitudinal extent of the door jamb, a hinge leaf having a straight portion pivoted to said plates and an arcuate portion pivoted to the hinge edge of the door, and a guide link having a straight portion pivoted to said plates and

an arcuate portion pivoted to the hinge edge of the door whereby said hinge leaf and said guide link at least partially extend into the space between said plates when the door is closed.
